UNITED STATES PATENT OFFICE.

JOHN FRASER, PATRICK FRASER, AND NORMAN FRASER, OF ARBROATH, SCOTLAND.

TWISTING MACHINERY.

SPECIFICATION forming part of Letters Patent No. 634,407, dated October 3, 1899.

Application filed December 20, 1897. Serial No. 662,593. (No model.)

To all whom it may concern:

Be it known that we, JOHN FRASER, PATRICK FRASER, and NORMAN FRASER, subjects of the Queen of Great Britain and Ireland, and 5 residents of Arbroath, Scotland, have invented certain Improvements in Twisting Machinery, (for which we have obtained a British Patent, No. 239, dated January 4, 1895,) of which the following is a specification.

10 Our said invention relates to twisting machinery of the kind in which the yarns or threads to be twisted together are drawn through a guide-eye by mechanism arranged in connection with the flier, which twists them and delivers them to the bobbin, upon 15 which they are wound; and our object is to provide, in connection with the guide-eye, mechanism which on a knot or other obstruction on the yarn meeting the guide-eye 20 will act on the stop-motion mechanism of the machine and prevent breakage of the yarn. The guide-eye may consist of a hole formed in an otherwise-solid piece, as is usually the case, or it may be in two or more pieces, which 25 by the action of a weight or equivalent are made to press uniformly on the passing yarn or thread notwithstanding inequalities in its thickness.

Figure 1 of the drawings is a horizontal 30 section, and Fig. 2 is a vertical section. Certain parts shown in Fig. 2 are for convenience not shown in Fig. 1.

In the drawings the same reference-letters are used to mark the same or like parts wherever they are repeated.

35 The part containing the guide-eye A is, according to the example shown in the drawings, formed in two pieces, one—the main body part B—having one half of the eye in it or at the inner end of a groove in a small part C, fixed to it, while the other piece D is made with a tongue E, having the other half of the 40 guide formed in its edge, the tongue projecting into the groove in the part C of the main body part. The main body part B is in the

form of a lever centered on a pin G, fixed in a bracket H on a vertical rod J, and is held up by an adjustable spring K. Pressure is applied to the movable piece D by a bell-crank lever L, acted on by an adjustable 50 weight M, (or it might be a spring.) The lever L is centered on a pin N, fixed in a boss formed on the main body part B, and the movable piece D is attached to it by a pin P. The bottom end of the eye A may be slightly 55 flared to suit the increased size of the combined yarns due to the twisting action. The main body part B, forming the lever, is depressed when a knot or other obstruction offers to pass through the guide-eye A and by 60 a wire or rod Q moves a bell-crank catch R, supporting the stop-motion device S, out of the way and allows said device to drop to stop the action of the machine, and thereby prevent breakage of the yarn. This may be done 65 by allowing the device S, on dropping, to shift the driving-cord T from the fast pulley U to the loose pulley W or in any other well-known way. The machine may be restarted by hand. 70

We claim as our invention—

In twisting machinery, a lever containing a guide-eye in two parts, one movable with reference to the other, and means for pressing the two parts of the eye toward each other, 75 in combination with a bracket to which said lever is pivoted, means to sustain the lever, a stop-motion device, a catch for the latter and means connecting the catch and lever, substantially as and for the purpose described. 80

In testimony whereof we have signed our names to this specification in the presence of two subscribing witnesses.

JOHN FRASER.
PATRICK FRASER.
NORMAN FRASER.
